BENJAMIN F. MIESSNER, OF SOUTH ORANGE, NEW JERSEY, ASSIGNOR, BY MESNE ASSIGNMENTS, TO RADIO CORPORATION OF AMERICA, OF NEW YORK, N. Y., A CORPORATION OF DELAWARE

ELECTRICAL SIGNAL AMPLIFYING AND REPEATING SYSTEM

Application filed May 13, 1925. Serial No. 29,859.

While my invention relates generally to electrical signal amplifying and repeating systems, it is described herein more particularly with reference to such systems used in the reception of high frequency electrical signals, transmitted through space and over wires, wherein three electrode vacuum tubes are employed as the amplifying and repeating devices.

10 An object of my invention is to improve upon the results which have been heretofore obtained when other than steady sources of potential have been employed for energizing the amplifying and repeating devices to 15 render them operative, particularly where other than steady sources of potential are used for energizing the filament and plate circuits of three electrode vacuum tubes. The invention resides in certain novel features whereby the "hum" in the telephones or other translating device resulting from such use of unsteady potentials is materially reduced.

The art has endeavored to substitute for 20 the battery form of energy supply to plate circuits of vacuum tubes other sources such as rectified and filtered commercial frequency alternating current and filtered machine generated direct current. No processes of rectification and filtration have as 25 yet been devised which do not leave substantial ripples in such plate current supply, and these ripples become particularly annoying if the system includes several stages of 30 audio frequency amplification to magnify in the output end the ripples in the earlier stages of the system. Similar unsteady sources of supply for heating the filaments of 35 vacuum tubes result in a varying difference of potential between the grid and filament due to a distributed drop of potential across the filament as well as a varying filament temperature giving rise to varying electron emission from the filament, this latter effect 40 being more accentuated in the case of filaments designed for high temperature operation. These filament effects also manifest themselves as variations or ripples in the plate current of the tube and are available 45 for magnification if the system includes

multiple stages of audio frequency amplification. A vacuum tube amplifying system including such sources of energy supply invariably suffers from an annoying "hum" in the telephones or loud speaker characteristic of the variations in the source of supply. There are many practical and economical advantages in substituting the hereinbefore mentioned sources of supply for the battery form now in most extensive use, and it is an object of my invention to eliminate in a practical sense or decrease the hum creating currents to such an extent that there will be no annoying "hum."

I have found that the hum may be most effectively eliminated to practical extents by independently creating ripples or current variations of similar characteristics and like values to those created in the amplifying system through using the aforementioned unsteady sources of supply, and then balancing the one set of variations by the other. The manner in which I accomplish this result and other novel features of my invention will be best understood by the following description taken in conjunction with the accompanying drawings, wherein,

Fig. 1 is a circuit diagram of a vacuum tube system employing my invention and illustrated in use as a receiver of high frequency currents transmitted over wires, and

Fig. 2 is another circuit diagram of a vacuum tube system illustrated in use as a radio receiving system, and in which a single vacuum tube functions both as a balancer and as an amplifier, an additional feature of my invention.

In Fig. 1, 1 and 2 represent two wires of an alternating current power line across which is connected the primary winding 3 of a transformer, which transformer has four secondary windings, 4, 5, 6 and 7, respectively. Winding 7 has at least half the number of turns of winding 6 and is also preferably wound in an electrically opposed sense to 6 so that the potential at the terminal 7' is 90 always substantially the same as the midpoint potential of the winding 6. Across the power lines 1, 2 there is shown connected a high frequency path including a condenser 100

8, which may or may not be variable, and the primary winding 9 of a radio frequency transformer, the secondary of which is included in the detector circuit 10 comprising 5 a detecting device 11, variable condenser 12 and primary winding 13 of an audio frequency transformer 14. High frequency carrier current, modulated in accordance with signals to be transmitted, is impressed 10 upon the power lines at the central power station, or sub-station—irrespective of low frequency power current—and is thus conveyed up to and through the primary winding 9 whence it is induced into the secondary 15 15 of the detector circuit 10. The modulated high frequency current is acted upon in the usual way in the detector circuit to produce audible frequency current effects characteristic of the modulations, the latter 20 being induced through audio frequency transformer 14 to the input circuit of vacuum tube amplifier 16, wherein they are amplified and passed through audio frequency transformer 17 into the second audio frequency amplifier 18, the output circuit of 25 which includes a loud speaking or other translating instrument 19.

Vacuum tube 20 functions as a creator of current variations for neutralizing or partially neutralizing the low frequency fluctuations in the output of vacuum tube 16 due to the use of alternating current filament supply and rectified alternating current plate supply all in a manner more fully described. 30 It will be noted that filaments 21, 22 and 23 of vacuum tubes 16, 18 and 20, respectively are all connected in parallel to the terminals of secondary winding 6 of the power transformer. The filaments are therefore supplied with alternating current of low frequency. 35

The plate circuits of the three vacuum tubes are supplied with unidirectional fluctuating current derived from rectifying and 40 filtering alternating current, there being provided a rectifier 24, which may be a vacuum tube, or any other suitable rectifier or plurality of rectifiers connected in parallel. The filament 25 of rectifier tube 24 is fed with alternating current from the secondary winding 4. Alternating space current of 45 proper potential is supplied to the rectifier tube by means of secondary winding 5. Since, in the arrangement illustrated, one rectifier tube only is provided, but one half the alternating current cycle is utilized. The utilized half cycle is impressed from the secondary winding 5 and rectifier 24, through an electrical filter to the plate circuits of all 50 the vacuum tubes. The filtering arrangement whereby the rectified alternating current is filtered or smoothed out to form an approximation to a continuous current is illustrated as comprising three shunt condensers 26, 27 and 28 and a series resistance 55 60 65

29. Any suitable form of filter may be employed.

Primary winding 30 of audio transformer 17 is included in the output circuit of vacuum tube 16 and primary winding 31 of transformer 32 is included in the output circuit of tube 20. Both transformers act on the input circuit of vacuum tube 18. The windings of transformers 17 and 32 are arranged so that currents arising in their respective tubes 16 75 and 20 act differentially on the input circuit of vacuum tube 18.

With the desired signal currents impressed upon the input circuit of vacuum tube 16 and to the exclusion of tube 20 there is no cancellation or opposing of these desired currents during their input from tube 16 to tube 18, and they therefore go through the system and are amplified for use in the translating device 19. If however, vacuum tube 20 is chosen 80 to have substantially the same characteristics as vacuum tube 16, and being, as illustrated, excited in both plate and filament circuits from the same sources as tube 16, then there are created like variations other than signal 85 currents to those in tube 16 which oppose or cancel on input to tube 18.

I have not shown a balancing tube provided for the second amplifier tube 18 because I have found in practice that the second balancer may be omitted without the hum becoming over-objectionable. In the first place variations arising in this last tube are not further amplified to the same extent as would be unneutralized variations arising in preceding tubes and passed on to this last tube. Also a slight overbalance may be accomplished in the preceding tube, the residual being utilized to balance undesired variations in the last tube and, being amplified, only a small overbalance or residual is needed to balance much larger variations in the last tube. Such an overbalance, and the phase of it, may be accomplished by interchanging tubes 16 and 20, as it would be rare to find two tubes exactly alike, or adjusting the potentiometer 37 from which wire 35 leads to the grids of tubes 16 and 18. This adjustment changes the alternating current potential on the grids, but since the grid of tube 16 is excited through secondary winding of transformer 14 and the grid of tube 20 is in a non-reactive lead, there would result a difference in grid effects sufficient to bring about an overbalance. Of course, other suitable devices for adjustment well within the skill of the art may be included in the system. The result of such overbalance is to impress on the grid of tube 18 variations in potential which reduce or neutralize variations in the plate circuit of tube 18 that are caused by the varying potential supplied by the rectifier and filter, and by the alternating heating current in the filament of tube 18. Or a balancer tube may be used 110 115 120 125 130 in conjunction with tube 18 in the same man-

ner as illustrated for tube 16 if a great nicety of balance in the system is required, but for ordinary practice a small amount of hum is not objectionable, being completely masked by any signal of fair intensity.

A grid biasing battery 38 may or may not be employed.

A ground connection is often found desirable. For the purpose of grounding the circuit a two-way switch 39 is provided, one contact of which goes directly to ground and the other through a condenser 40 to the grounded side of the power transmission line. It is contemplated that whichever ground connection gives the better result, in any instance, would be used.

Fig. 2 illustrates an arrangement embodying my invention more particularly adapted for radio reception, and wherein I employ a vacuum tube in the dual capacity of balancer and amplifier. In the system of Fig. 2 modulated high frequency currents are collected by the antenna 41 and passed through radio frequency transformer 42 to the tuned 25 input circuit 43 of a radio frequency amplifier tube 44. The output circuit of amplifier tube 44 includes the primary winding 45 of a radio frequency transformer 46, the secondary of which is included in the input circuit of a second radio frequency amplifier tube 47. The input circuit of this tube is tuned by means of a variable condenser 48. The output circuit of amplifier tube 47 includes the primary winding 49 of the radio frequency transformer 50, the secondary winding of which is included, together with the variable condenser 51, in the input circuit of a third amplifier tube 52. The radio frequency output of amplifier tube 52 is impressed through transformer 53 upon a detector circuit 54 which includes a crystal or other detector 55. The detector circuit functions in the usual manner to convert the amplified radio frequency current into 40 audio frequency effects corresponding to the modulations. The detected audio frequency modulations are passed through the primary winding 56 of an audio frequency transformer 57 and impressed upon the input circuit of tube 47 which, as was shown, also functions as a radio frequency amplifier tube. This tube also functions as the first audio amplifier and includes in its output circuit the primary winding 58 of an audio frequency transformer 59. The audio frequency currents pass 45 from the primary 58 to the secondary 60 of transformer 59 and are thus impressed upon the input circuit of amplifier tube 52 which also functions as a radio frequency amplifier. The output circuit of tube 52 includes a translating device 61 which is shunted by a condenser 62 forming a by-pass for the radio frequency current.

Tube 44 functions as the balancer for the first audio frequency stage tube 47 in the same manner as was described in connection with

Fig. 1. This role of balancer does not interfere with its other function in the system, that of radio frequency amplifier. The balance is secured through winding 63 in the plate circuit of tube 44 acting differentially or oppositely to winding 58 in the plate circuit of tube 47.

As described in connection with Fig. 1, an additional balancing tube may be provided for balancing out the hum arising in vacuum tube 52, but as explained in connection with the description of the circuit of Fig. 1, the hum is not usually regarded as excessive with the second balancing tube omitted, and may easily be balanced out or satisfactorily reduced by hum current energy coming from the preceding tubes.

The provisions in Fig. 2 for converting alternating current into unidirectional current for the plate supply and heating the filaments with alternating currents are identical with those in the circuit of Fig. 1 and it is thought require no further explanation.

It is obvious that my invention is capable of being embodied in many different circuit arrangements and should not be construed as limited to those herein illustrated and described, but only by the scope of the appended claims.

I claim:

1. A system adapted to amplify high frequency currents modulated at lower signaling frequency including amplifying repeaters, a detector dividing the system into high frequency and low frequency amplifying portions, means for energizing the repeaters in both portions for operation from fluctuating sources of potential, and means for opposing the output of one or more of the repeaters of the low frequency portion by the low frequency output due to fluctuating potential energization of one or more of the repeaters of the high frequency portion.

2. A system adapted to amplify high frequency currents modulated at lower signaling frequency including a high frequency amplifier, a detector, a low frequency amplifier, means for energizing the amplifiers for operation from fluctuating sources of potential and means for opposing the output of the low frequency amplifier with the low frequency output due to fluctuating potential energization of the high frequency amplifier.

3. A system adapted to amplify high frequency electrical currents modulated at lower signaling frequency including amplifying repeaters, means for energizing the repeaters for operation from fluctuating sources of potential, means for employing the repeaters as amplifiers of the currents in high frequency form, means for converting the high frequency current energy to currents of the lower signaling frequency, means for returning and passing the low frequency

currents through a number less than all of the repeaters, and means for opposing the output of one or more of said low frequency signal excited repeaters by the low frequency 5 output due to fluctuating potential energization of the non-low frequency signal current excited repeaters.

4. In a wave signal receiving system, a pair of three-electrode vacuum tubes each comprising a filament, a grid and a plate, a source of alternating filament heating current connected to said filaments, output circuits for said tubes, said output circuits being differentially related in such manner that equal 10 and simultaneous space current variations in said tubes oppose and substantially cancel each other out and means whereby both of said tubes are rendered operable as radio frequency amplifiers and one of said tubes is 15 rendered operable as an audio frequency amplifier.

5. A signal current amplifying system employing a plurality of three-electrode vacuum tubes arranged for multi-stage amplification 20 of signaling current, a source of current supply for energizing a circuit of each of said tubes and tending to cause periodic disturbing variations in the plate circuit of said tubes, a coupling between the plate circuit of one of 25 said tubes and the grid circuit of another of said tubes, said coupling being so arranged that variations produced in the grid circuit by variations in the plate circuit which is 30 coupled thereto neutralize the variations in 35 the plate circuit of said other tube.

6. In a signal current amplifying system employing three-electrode vacuum tubes the plate circuits of which are subject to current variations of similar frequency and phase, 40 means for reversing the phase of such variations in the plate circuit of one of the tubes and applying the reverse variations to the grid circuit of another of the tubes, and adjustable means for altering said reverse variations, said means including a circuit for 45 supplying alternating current for heating the tube filaments and an adjustable connection between the grids of said tubes and 50 points of different potential of said supply circuit.

7. In a signal amplifying system, a pair of three-electrode vacuum tubes, means for exciting one of the circuits of each tube with current at a potential which varies at audio 55 frequency, thereby tending to produce in the plate circuits of said tubes disturbing variations of current at a corresponding frequency, and an audio frequency coupling between the 60 grid circuit of one tube and the plate circuit of the other tube, said coupling being so arranged that the disturbing current variations in the plate circuit of said other tube are impressed on the grid circuit of said one tube 65 in such a way as to neutralize the disturbing

current variations in the plate circuit of the one tube.

8. In an electrical signal amplifying system, a pair of three-electrode vacuum tubes, an audio frequency coupling between the 70 grid circuit of one of the tubes and the plate circuit of the other tube, one of said tubes having an inductive and the other of said tubes having a non-inductive grid circuit, a circuit for supplying alternating current to 75 the filaments of said tubes for heating the same, and a connection between said grid circuits and said supply circuit, said connection being adjustable to points of different potential of said supply circuit, which points 80 are in the neighborhood of the point of zero potential of said supply circuit.

9. In a signal current amplifying system employing three-electrode vacuum tubes arranged for multi-stage amplification of signaling current, means for energizing each of said tubes for operation from a common source of current energy tending to cause periodic disturbing variations in the plate circuits thereof, means for passing to the 90 grid circuit of a succeeding tube some of the disturbing energy of a preceding tube of phase to oppose the disturbing energy in the plate circuit of said succeeding tube, and means for proportioning said passed energy 95 in accordance with the amplification of said succeeding tube to substantially neutralize the disturbing energy in the plate circuit thereof.

10. In a signal current amplifying system 100 employing three-electrode vacuum tubes arranged for multi-stage amplification of signaling current, means for energizing each of said tubes for operation from a common source of current energy tending to cause 105 periodic disturbing variations in the plate circuits thereof, and connected to produce said variations in like phase, and means for passing to the grid circuit of one of said tubes some of the disturbing energy of another one of said tubes of phase to neutralize the disturbing variations in the plate circuit of said first tube.

11. In an audio frequency signal current amplifying system employing three-electrode vacuum tubes arranged for multi-stage amplification, means for energizing each of said tubes for operation from a common source of commercial alternating current 110 energy tending to cause periodic audio frequency disturbing variations in the plate circuits thereof, and connected to produce said variations in like phase, means for transferring signal current energy and disturbing current energy from one tube to 115 another, said means being arranged to transfer disturbing current energy of a preceding tube to neutralize disturbing current energy of a succeeding tube.

12. In a signal current amplifying system 120

employing three-electrode vacuum tubes arranged for multi-stage amplification, means for energizing each of said tubes at least in part for operation from a common source of alternating current connected to said tubes so that the disturbing variations are produced in like phase, and means for passing energizing energy from one of said tubes through the grid circuit of another one of said tubes in a phase to oppose the energizing fluctuations in the plate circuit of said other tube.

13. In a signal current amplifying system employing three-electrode vacuum tubes arranged for multi-stage amplification, means for energizing for operation like electrodes of each of said tubes from a common source of periodically fluctuating current connected to said electrodes so that the disturbing variations are produced in like phase, and means for passing energizing fluctuating energy from one of said tubes through the grid circuit of another one of said tubes in a phase to oppose the energizing current fluctuations in the plate circuit of said other tube.

14. In a signal current amplifying system employing three-electrode vacuum tubes arranged for multi-stage amplification, means for energizing for operation like electrodes of each of said tubes from a common source of periodically fluctuating current, and means for passing energizing fluctuating energy from one of said tubes through the grid circuit of another one of said tubes to oppose the energizing current fluctuations in the plate circuit of said other tube, and means proportioning the amount of said energy so passed to the energy in the plate circuit of said other tube in accordance with the amplification of said other tube.

15. In a signal current amplifying system employing a pair of three-electrode vacuum tubes arranged for multi-stage amplification and having like electrodes energized for operation from a common source of periodically fluctuating current, the method of reducing hum disturbances which consists of opposing the fluctuations of energizing current in one of said tubes by lesser fluctuations derived from another of said tubes after amplification at least by said first tube.

16. In a signal current amplifying system employing three-electrode vacuum tubes arranged for multi-stage amplification and having like electrodes energized for operation from a common source of periodically fluctuating current, the method of reducing hum disturbances which consists of opposing the fluctuations of energizing current in one of said tubes by fluctuations derived from another of said tubes and amplified at least by said first tube, and proportioning said derived energy to said opposed energy in accordance with said amplification.

17. In a signal current amplifying sys-

tem including three-electrode vacuum tubes, means for employing some of said tubes as radio frequency amplifiers and some of said tubes as audio frequency amplifiers, means for energizing like electrodes of said tubes for operation from a common source of periodically fluctuating current energy, and means for neutralizing fluctuating components of said energy in said audio frequency portion with fluctuating energy derived from the energizing energy of said radio frequency portion.

18. In a signal current amplifying system including a plurality of three-electrode vacuum tubes connected in cascade to amplify audio frequency currents, means for energizing like electrodes of said tubes for operation from a common source of periodically fluctuating current energy connected to said electrodes so that the disturbing variations are produced in like phase, and means for neutralizing fluctuating components of said energy in one of said tubes with fluctuating energy derived from the energizing energy of another of said tubes.

19. In a signal current amplifying system employing three electrode vacuum tubes arranged for multi-stage amplification of signaling current, means connecting the filaments of said tubes in parallel to a common source of alternating current, whereby the resulting periodic disturbing variations in the plate circuits of said tubes are of like phase, and means for passing to the grid circuit of one of said tubes some of the disturbing energy of another one of said tubes of phase to neutralize the disturbing variations in the plate circuit of said first tube.

In testimony whereof I affix my signature.

BENJAMIN F. MIESSNER.

DISCLAIMER

1,789,950.—*Benjamin F. Miessner*, South Orange, N. J. ELECTRICAL SIGNAL AMPLIFYING AND REPEATING SYSTEM. Patent dated January 20, 1931. Disclaimer filed January 20, 1932, by the assignee, *Radio Corporation of America*.

Hereby enters this disclaimer to the said claims of said Letters Patent which are in the following words, to wit:

“Claim 5: A signal current amplifying system employing a plurality of three-electrode vacuum tubes arranged for multi-stage amplification of signaling current, a source of current supply for energizing a circuit of each of said tubes and tending to cause periodic disturbing variations in the plate circuit of said tubes, a coupling between the plate circuit of one of said tubes and the grid circuit of another of said tubes, said coupling being so arranged that variations produced in the grid circuit by variations in the plate circuit which is coupled thereto neutralize the variations in the plate circuit of said other tube.”

“Claim 10: In a signal current amplifying system employing three-electrode vacuum tubes arranged for multi-stage amplification of signaling current, means for energizing each of said tubes for operation from a common source of current energy tending to cause periodic disturbing variations in the plate circuits thereof, and connected to produce said variations in like phase, and means for passing to the grid circuit of one of said tubes some of the disturbing energy of another one of said tubes of phase to neutralize the disturbing variations in the plate circuit of said first tube.

“Claim 11: In an audio frequency signal current amplifying system employing three-electrode vacuum tubes arranged for multi-stage amplification, means for energizing each of said tubes for operation from a common source of commercial alternating current energy tending to cause periodic audio frequency disturbing variations in the plate circuits thereof, and connected to produce said variations in like phase, means for transferring signal current energy and disturbing current energy from one tube to another; said means being arranged to transfer disturbing current energy of a preceding tube to neutralize disturbing current energy of a succeeding tube.

“Claim 12: In a signal current amplifying system employing three-electrode vacuum tubes arranged for multi-stage amplification, means for energizing each of said tubes at least in part for operation from a common source of alternating current connected to said tubes so that the disturbing variations are produced in like phase, and means for passing energizing energy from one of said tubes through the grid circuit of another one of said tubes in a phase to oppose the energizing fluctuations in the plate circuit of said other tube.

“Claim 13: In a signal current amplifying system employing three-electrode vacuum tubes arranged for multi-stage amplification, means for energizing for operation like electrodes of each of said tubes from a common source of periodically fluctuating current connected to said electrodes so that the disturbing variations are produced in like phase, and means for passing energizing fluctuating energy from one of said tubes through the grid circuit of another one of said tubes in a phase to oppose the energizing current fluctuations in the plate circuit of said other tube.”

“Claim 15: In a signal current amplifying system employing a pair of three-electrode vacuum tubes arranged for multi-stage amplification and having like electrodes energized for operation from a common source of periodically fluctuating current, the method of reducing hum disturbances which consists of opposing the fluctuations of energizing current in one of said tubes by lesser fluctuations derived from another of said tubes after amplification at least by said first tube.”

“Claim 18: In a signal current amplifying system including a plurality of three-electrode vacuum tubes connected in cascade to amplify audio frequency currents, means for energizing like electrodes of said tubes for operation from a common source of periodically fluctuating current energy connected to said electrodes so that the disturbing variations are produced in like phase, and means for neutralizing fluctuating components of said energy in one of said tubes with fluctuating energy derived from the energizing energy of another of said tubes.”

Your petitioner hereby enters this disclaimer to the combination covered by claim 7 of said patent aforesaid except when a single audio frequency coupling is used between the grid circuit of one tube and the plate circuit of the other tube for transmitting both signal currents and disturbing current variations.

[Official Gazette March 1, 1932.]
